UNITED STATES PATENT OFFICE

LEWIS J. BAZZONI, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

SHOE HEEL AND METHOD OF MANUFACTURING THE SAME

Application filed March 8, 1929. Serial No. 345,425.

This invention relates to improvements in shoe heels and methods of manufacturing the same.

The lateral breast corners of heels, on account of their sharpness and exposed location, are particularly susceptible to wear and if the heels are covered the portions of the covering which overlie the breast corners of the heels are more liable to become worn or damaged than other portions of the covering. Moreover, in cases where marginal portions of a heel covering are turned or tucked into recesses or grooves in the heel, the portions of the covering which overlie the edges of the recesses or grooves are also particularly susceptible to wear and injury.

One object of the present invention is to provide an improved heel having portions which are reinforced against wear and injury.

With this object in view, one feature of the invention consists in a heel having a fitted portion adapted to receive a member for reinforcing a portion of the heel, and a reinforcing member secured to said fitted portion of the heel. As herein illustrated, the heels are fitted by having their lateral breast corners beveled or rabbeted to prepare them for the reception of breast corner reinforcing members, and a breast corner reinforcing member in the form of a strip of wear-resisting material is applied to each prepared corner portion of the heel, and secured thereto by adhesive or other suitable means, to replace the material removed by the rabbeting or beveling operations, and thereby to provide lateral heel breast corners which are less susceptible to wear and injury than are the breast corners of a normal heel. The invention is not, however, necessarily restricted to reinforcement of the lateral breast corners of heels inasmuch as other portions which are susceptible to wear or injury may advantageously be reinforced. Neither is the invention necessarily restricted to the performance of beveling,

rabbeting or other fitting operations upon heels of normal configuration since it is within the spirit of the invention to provide heels made, for example, of plastic material, which are initially molded or otherwise formed with the desired reduced or fitted portions for

receiving the reinforcing members. In its application to the reinforcement of the breast corners of heels the invention is useful, irrespective of whether the heel is to be covered after the breast corners have been reinforced or whether the heel is to remain uncovered in the finished shoe.

In accordance with another feature of the invention which is applicable to embodiment in covered heels, the illustrated heel breast corner reinforcing strips are composed of the same material as that to be employed for covering the heel. As herein illustrated the reinforcing strips and the heel covering are both composed of celluloid although leather or other suitable material may be employed. With this construction, when the portions of the heel covering which overlie the breast corner reinforcing strips become partially worn away so as to expose to view portions of the reinforcing strips, the worn condition of the heel covering will be less noticeable because of the fact that the exposed portions of the heel beneath the worn portions of the cover are composed of the same material as the cover itself.

The invention is not limited, however, to the use of reinforcing strips of the same material as the heel covering, it being pointed out that it is advantageous in some instances to employ reinforcing strips of metal or other material of greater wear-resisting characteristics than the heel covering material. Such reinforcing strips may be secured in place in any suitable manner as, for example, by the use of small nails, and they are especially useful in connection with heels having painted or coated surfaces.

The invention further resides in an improved method of making heels which consists in forming a heel with a fitted portion adapted to receive a reinforcing member, and securing a reinforcing member to said fitted portion of the heel. In one exemplification herein shown of this aspect of the invention, the lateral breast corners of a heel are beveled and the material removed by the beveling operation is replaced by reinforcing material initially applied to the heel in the form of strips not shaped to the final cross-sectional

contour ultimately desired, and the strips are subsequently reduced, as by buffing or sanding operations, so that the cross-sectional curvature of the exposed side of each strip blends with the cross-sectional curvature of the side of the heel.

The invention will be described with reference to the accompanying drawings, illustrating certain preferred embodiments there-
10 of, in which

Fig. 1 is a perspective view of an uncovered Cuban heel having reinforcing strips applied to its lateral breast corners in accordance with the present invention;

15 Fig. 2 is a cross-sectional view of the heel shown in Fig. 1;

Fig. 3 is a perspective view of a covered heel having reinforcing strips at its breast corners;

20 Fig. 4 is a fragmentary cross-sectional view, on an enlarged scale, of the heel shown in Fig. 3;

25 Figs. 5 and 6 are fragmentary sectional views, showing modifications of the construction shown in Figs. 3 and 4;

30 Fig. 7 is a cross-sectional view of a portion of a heel having its lateral breast corners beveled to receive reinforcing strips and illustrating one manner of applying the strips to the beveled corners;

Fig. 8 is a fragmentary sectional view illustrating a further stage in the process of making a covered heel having beveled and reinforced breast corners;

35 Fig. 9 is a view similar to Fig. 8 but illustrating the use of a single piece of material for covering the sides and breast of the heel and also the use of reinforcing strips at the center of the heel breast adjacent to the meeting ends of the covering;

40 Fig. 10 is a fragmentary sectional view illustrating one of the steps in another method of applying a breast corner reinforcing strip to a heel; and

45 Fig. 11 is a view similar to Fig. 10 but showing the reinforced heel as it appears in its finished form.

Referring to Figs. 1 to 6, inclusive, of the drawings, there is indicated at H a wooden 50 Cuban heel having its opposite lateral breast corners rabbeted, as shown at R, to receive reinforcing strips such as the strips 14 which may be made of any suitable wear-resisting material. As shown in Figs. 1 and 2, the

55 reinforcing strips 14 are made of such cross-sectional shape as to fit within the rabbeted corners in such a manner as to replace the material removed by the rabbeting operation so that the heels, after the reinforcing strips

60 14 have been applied thereto, are of normal cross-sectional shape at the breast corners. If the reinforcing strips are made of celluloid they may be applied while the celluloid is

65 in a softened state, in which case the celluloid upon drying will adhere to the heel body

without the necessity of employing any special adhesive. If material other than celluloid is employed for the reinforcing strips, the strips may be securely held in place by the use of any suitable adhesive such as celluloid cement or by other suitable securing means.

The reinforcing strips 14 may be made of such material as materially to strengthen the breast corners as well as to reinforce them against wear. Moreover, 70 heels like that shown in Figs. 1 and 2, after having their breast corners reinforced as above described, may be painted or coated with material of the same color and appearance, if not of the same physical characteristics, as the reinforcing strips.

In the use of such coated heels, when the coating becomes worn away at the breast corners the reinforcing strips will then become exposed but inasmuch as the strips are of the same 80 color and appearance as the coating it will not be readily apparent that the coating has been removed at the corners. Furthermore, the exposed reinforcing strips will withstand a substantial amount of additional wear before any portion of the wooden heel body 90 will be exposed to view in the vicinity of the breast corners.

95 In the covered heel constructions exemplified in Figs. 3, 4 and 6 a breast covering 16 and a side covering 18 is shown, each consisting of a thin sheet of celluloid, and the reinforcing strips 14 are also made of celluloid so that as the margins of the breast or

100 side coverings which overlap the reinforcing strips wear away the material thus exposed to view will have the same physical characteristics as the covering itself and consequently the worn condition of the covering

105 will be less noticeable. As shown in Fig. 4, the lateral margins of the breast covering 16 are received in the rabbeted corner portions R between the reinforcing strips 14 and the sides of the recess formed by the rabbeting operation.

110 The side covering 18, however, which extends around the rear and sides of the heel overlaps the reinforcing strips and is trimmed flush with the breast surface of the heel. The coverings 16 and 18 and the reinforcing strips each being made of celluloid and applied to the heel in a semi-solvent condition, the cover margins will become firmly attached or fused to the reinforcing strips when the celluloid becomes dry.

115 As shown in Fig. 5, both the breast covering 16 and the side covering 18 have their margins received in the rabbeted corner portions R and are thus securely held in place by the strips 14. In Fig. 6 both the side and breast coverings are shown as overlapping 120 the reinforcing strip 14 so as entirely to conceal it from view.

125 In the constructions exemplified in Figs. 7, 8 and 9 the breast corners of the heel H are beveled as indicated at B instead of being

rabbeted as hereinbefore described, and the material removed by relieving the corners in this manner is replaced by wedge-shaped reinforcing strips 14a. In heels having beveled faces, such as the faces B at the breast corners, the reinforcing strips are advantageously applied in the rectangular cross-sectional form shown at 20 in Fig. 7 and reduced to the desired wedge shape by sanding 10 or other suitable operations after the strips have been secured in place. As exemplified in Fig. 8 the reinforcing strips are left exposed at the breast of the heel between separate side and breast coverings 18 and 16, respectively, while in Fig. 9 a one-piece cover 22 extends over both the side and breast surfaces of the heel entirely concealing the reinforcing strips.

In each embodiment of the invention hereinbefore specifically referred to, the heel has been fitted by the cutting away of material from its lateral breast corner portions to adapt the heel to receive breast corner reinforcing members. It is to be understood, 25 however, that the fitting of the heels and the application of reinforcing members is not necessarily limited to the breast corner portions of the heels since the invention is applicable also to the reinforcing of other 30 portions of the heels such as portions where a joint is formed between two adjacent margins of a covering, as shown, for example, in Fig. 9 wherein reinforcing strips 14b are inserted at opposite sides of a groove 24 in 35 the center of the heel breast. In this construction, the meeting ends of a one-piece heel cover 22 are tucked into the groove 24 between the strips 14b and the strips define the edges of the opening into which the cover 40 margins are tucked and reinforce the portions of the cover which overlie these edges.

As shown at 14c in Fig. 11 the reinforcing strips may be made of such cross-sectional shape that the outer side faces of the strips 45 will blend with the cross-sectional curvature of the sides of the heel without the necessity of beveling, rabbeting or otherwise fitting the corner portions of the heel to receive the strips. In accordance with a practice found 50 to be advantageous reinforcing strips may be employed which are initially of rectangular cross-sectional form such as that shown at 26 in Fig. 10, and the strips may be reduced by sanding or buffing operations to the 55 desired finished form shown in Fig. 11.

In cases where the reinforcing strips are to be partially exposed in the finished heels these strips may, as herein shown, be arranged with edge portions projecting forwardly beyond the breast surface of the heel so that a breast covering may be applied between the reinforcing strips with the exposed surface of the breast covering flush with the 60 forwardly projecting edge portions of the reinforcing strips. Furthermore, if the re-

inforcing strips are to be exposed in the finished heels the strips may be made of such a color as to contrast with the color of the heel covering, thus producing an ornamental inlay effect which is highly desirable in certain types of shoes. 70

Having described my invention, what I claim as new and desire to secure by Letters Patent of the United States is:

1. A heel having a cut-away portion located and adapted to receive a member for reinforcing the corner between the heel breast and one side of the heel, and a member for reinforcing said corner secured to said cut-away portion of the heel, said member being shaped and arranged to compensate for the material cut away and thus to preserve the normal side contour of the heel. 75

2. A heel having a reduced corner portion, and a piece of reinforcing material applied to said corner portion. 85

3. A heel having its lateral breast corners removed, and strips of wear-resisting material secured to the heel and arranged to replace the removed portions of the breast 90 corners. 90

4. A heel having beveled breast corner portions, and reinforcing strips secured upon said beveled portions, said strips being shaped to compensate for the material removed by the beveling operations and thus to preserve the normal contours of the sides of the heel. 95

5. A heel having a reduced corner portion reinforced by the application thereto of a strip of wear-resisting material, and separate coverings for the side and breast surfaces of the heel arranged at opposite sides of said reinforcing strip. 100

6. A heel having a reduced lateral breast edge portion, a reinforcing member applied to said reduced portion, and a heel covering overlapping said reinforcing member. 105

7. A heel having a reduced portion extending heightwise of the heel along one of its lateral breast edges, a celluloid reinforcing strip applied to said reduced portion, and a celluloid heel covering overlapping said reinforcing strip and secured thereto. 110

8. A heel having a reinforced breast corner, and a covering overlapping said corner. 115

9. A heel having a reinforced breast corner, and a covering overlying a portion of the reinforced corner, said corner having another portion exposed to wear to prevent injury to the heel and the covering. 120

10. A heel having reinforcing strips at the lateral corners of its breast, the strips having edge portions projecting forwardly beyond the breast surface, and a breast covering having its exposed side flush with the forwardly projecting edge portions of the reinforcing strips. 125

11. A heel having reinforcing strips at the lateral corners of its breast, the strips having 130

edge portions projecting forwardly beyond the breast surface, a covering for the sides of the heel overlying said strips, and a breast covering having its exposed side flush with the forwardly projecting edge portions of the reinforcing strips.

12. A heel having separate coverings for its breast and side surfaces, and exposed reinforcing strips of the same material as said coverings at the lateral breast corners between the side and breast coverings.

13. That improvement in methods of making heels which consists in reducing the lateral breast corners of a heel, replacing with heel-reinforcing material the material removed by the reducing operation, and shaping the reinforcing material to restore to said breast corners their original cross-sectional contours.

14. That improvement in methods of making heels which consists in beveling the lateral breast corners of a heel, and building up the beveled corners to restore them to their original shape by securing strips of wear-resisting material thereto.

15. That improvement in methods of making covered heels which consists in applying to the lateral breast corners of a heel reinforcing strips not shaped to final cross-sectional form, and thereafter reducing said strips to a cross-sectional contour blending with the cross-sectional contour of the heel.

16. That improvement in methods of making heels which consists in beveling the lateral breast corners of a heel, replacing the portions removed from the corners of the heel by securing to said beveled corners reinforcing strips of greater cross-sectional area than that ultimately desired, and thereafter shaping said strips to cause the cross-sectional curvature of their exposed surfaces to blend with the cross-sectional curvature of the sides of the heel.

17. That improvement in methods of making covered heels which consists in reducing the lateral breast corners of a heel, replacing the material removed by the reducing operation by reinforcing strips of celluloid, applying to the heel a celluloid cover having marginal portions adapted to overlap said strips, and fusing said cover margins and said strips together.

18. That improvement in methods of making covered heels which consists in beveling the lateral breast corners of a heel, securing to the beveled surfaces reinforcing strips of rectangular cross-section, and thereafter reducing the reinforcing strips to cause their outer surfaces to blend with the curvature of the side surfaces of the heel.

In testimony whereof I have signed my name to this specification.

LEWIS J. BAZZONI.
